BROWN BOVERI & CIE., OF BADEN, SWITZERLAND.

TIME-LIMIT RELAY.

1,284,849.

Specification of Letters Patent. Patented Nov. 12, 1913.

Application filed December 30, 1913. Serial No. 128,905.

To all whom it may concern:

Be it known that I, ALBERT AICHELE, a citizen of the Swiss Republic, residing at Wiesenstrasse, in the town of Baden, in Switzerland, have invented certain new and useful Improvements in or Relating to Time-Limit Relays, of which the following is a specification.

My earlier U. S. patent application Serial No. 62,000 which consists in improvements in time limit relays, specifies a time limit relay wherein in the case of an overload current the time mechanism is set in operation by a partial attraction of the armature of the electromagnet of the relay.

One of these improvements consists in means for enabling in case of very great overload currents, and especially in the case of a short-circuit, the main switch to be released for the instant with a by-passing of the said time mechanism. The means specified in the specification of the aforesaid application consists in an arrangement wherein the pawl that hinders the complete attraction of the electromagnet armature during the running down of the time mechanism, is connected to the electromagnet armature by a very strong spring.

The particular location of the time limit relay in the network may render this instantaneous release in the case of a short-circuit desirable or not. Further, it may easily happen in extending the network that a time limit relay which has hitherto possessed no instantaneous release in the case of a short-circuit, has to be converted into a relay capable of such release or not. Such a conversion can be effected in a known way by a mere turn of the hand.

An embodiment of this invention is illustrated in the accompanying drawings in conjunction with the parts necessary for illustrating the application of this invention to a time limit relay.

In these drawings:—

Figure 1 is a side elevation partly in vertical section of the complete device.

Fig. 2 is a cross-section through the armature extension at the apex of the angular notch of the armature extension.

Fig. 3 is a partial plan of the armature extension showing a detail.

1 is the core of the electromagnet; 3 is its armature pivoted on the pin 4; 5 is an extension of the armature; 7 is the pawl

6 is a strong spring for coupling the said pawl elastically to the armature 3. 8 is the latch adapted to engage and hold the said pawl 7.

In the form shown in the drawing by way of example, the electromagnet core 1, with overload coil 2 has an armature 3 that can pivot on the fixed axle 4. This armature has an extension 5 for operating the circuit breaker by way of the rod 20, and 65 is connected by a particularly powerful spring 6 to a pawl 7 that is likewise pivoted on the axle 4. The pawl 7 bears against a nose piece 8, pivoted at 9 in the free end of the bell crank lever 10, movable about the 70 fixed axle 11. The other arm of the lever 10 is engaged by the counter spring 12 of the electromagnet armature 3 which in the deenergized position presses a small shoulder 13 against and thus brakes the 75 rotor 14 which forms with the core 1 an asynchronous motor.

The time mechanism itself consists of the reducing gear 15 driving the toothed sector 16. This sector is rotatable about the 80 axle 9 and is brought into engagement with the gear 15 only when by the operation of the relay the lever 10 is rotated on the axle 11. The sector 16 has a stop-pin 17 which in the normal position bears against the fixed 85 pointer 18. By means of the latter the time of release can be regulated by hand. For the purpose of adjusting the strength of the releasing current the spring 12 may be stressed more or less by means of the 90 piece 19.

According to the present invention the spring 6 which passes through a slot 25 is attached to a small plate 21 which is located loose in an angular notch formed in the 95 armature extension 5. In this position A the plate 21 is pulled by the spring 6 against the side 22 of the said notch, and in its position B the said plate 21 is pulled against the side 23 of the said notch. The plate 100 21 is adapted to be pulled over by the finger in opposition to the spring 6, from the position A into the position B, in which movement the apex of the angle of the notch serves as a pivotal bearing for the said plate. 105 When the plate is in the position B it prevents the pawl 7 from moving relatively to the armature 3, since it places itself against the nose 24 of the pawl 7, and thus couples rigidly the parts 3 and 7 to- 110

gether. The armature must now move with it the entire time mechanism so that the latter cannot come into operation at all. As this, however, requires a considerably higher magnetic force, the attraction of the armature 3 in the position B of the lever 21 takes place only in the case of very high currents, that is to say, for instance in the case of short circuits.

10. What I claim is:—

1. In a time limit relay with instantaneous release of the main switch with bypassing of the time mechanism, of the type specified, the combination, with the relay 15 electromagnet, its armature pivotally connected thereto, and the pawl for preventing the complete attraction of said armature during the running down of the time mechanism, of an extension of said armature, a lever fulcrumed on said armature extension, and a spring attached at one end to said pawl and at its other end to said lever, the arrangement being such that on moving said lever by hand from one end position into the other, said spring will be stressed and thereby will have a locking action upon 40 said pawl.

2. In a time limit relay with instantaneous release of the main switch with by-passing of the time mechanism of the type specified, the combination, with the relay 20 electromagnet, its armature pivotally connected thereto, and the pawl for preventing the complete attraction of said armature during the running down of the time mechanism, of an extension of said armature having an angular notch, a plate-like lever fulcrumed 25 loosely in the apex of said angular notch, and a spring attached at one end to said pawl and at its other end to said plate-like lever, whereby on said plate-like lever being moved by hand in opposition to said spring into or out of engagement with said pawl, said plate-like lever will in each case be caused by said spring to bear against the corresponding side of said angular notch.

In testimony whereof I have signed my name to this specification.

ALBERT AICHELE.

complete attraction of said armature during 35 the running down of the time mechanism, of an extension of said armature, a lever fulcrumed on said armature extension, and a spring attached at one end to said pawl and at its other end to said lever, the arrangement being such that on moving said lever by hand from one end position into the other, said spring will be stressed and thereby will have a locking action upon 40 said pawl.

3. In a time limit relay with instantaneous release of the main switch with by-passing of the time mechanism of the type specified, the combination, with the relay 45 electromagnet, its armature pivotally connected 50 thereto, and the pawl for preventing the complete attraction of said armature during the running down of the time mechanism, of an extension of said armature having an angular notch, a plate-like lever fulcrumed 55 loosely in the apex of said angular notch, and a spring attached at one end to said pawl and at its other end to said plate-like lever, whereby on said plate-like lever being moved by hand in opposition to said 60 spring into or out of engagement with said pawl, said plate-like lever will in each case be caused by said spring to bear against the corresponding side of said angular notch.
